COMBINED PULL AND CATCH

John R. Morgan, Northbrook, Ill., assignor to Amerock Corporation, Rockford, Ill., a corporation of Illinois

Application April 4, 1957, Serial No. 45,593

Term of patent 14 years

(Cl. D10—8)

Fig. 2 is a perspective view.

Fig. 3 is a front view.

Fig. 4 is an enlarged sectional view taken along the line 4—4 in Fig. 1.

Fig. 5 is an enlarged sectional view taken along the line 5—5 in Fig. 1.

I claim:

The ornamental design for a combined pull and catch, substantially as shown.
